UNITED STATES PATENT OFFICE.

JAMES S. RAY, OF EAST HADDAM, CONNECTICUT.

DESIGN FOR COFFIN-HANDLE SOCKET.

Specification forming part of Design No. 6,592, dated April 15, 1873; application filed March 24, 1873.

To all whom it may concern:

Be it known that I, JAMES S. RAY, of East Haddam, in the county of Middlesex and State of Connecticut, have invented a new and original Design for a Coffin-Handle Socket, of which the following is a specification:

Figure 1 is a face view of my new design for the socket of a coffin-handle. Figs. 2 and 3 are profile sectional views thereof on the lines *c c* and *k k*, Fig. 1, respectively.

Similar letters of reference indicate corresponding parts in all the figures.

This invention relates to a new design for a rectangular socket of a coffin-handle; and consists in the general configuration of parts herein shown and described.

I form on the socket cross-bands *a a*, which divide its face into four equal, or nearly equal, sections or fields. The raised middle part *b* of the socket is also of rectangular outline, and

has a slightly-projecting narrow border, *d*, with square corner-pieces *e*, as shown. From this middle part the sides *f f* of the socket slant off in the form of hollow curves toward the edge or base, and terminate in ribbed or corrugated edges *g g*, except where the arms *a* cover them and at the corners *h* of the socket, which corners are not corrugated, but smooth, as shown. Suitable surface ornamentation may be applied to the elevated central part *b* and to the curved sides *f*, as indicated, or otherwise.

I claim as new and desire to secure by Letters Patent—

The design for the socket of a coffin-handle, as shown.

JAS. S. RAY.
